UNITED STATES PATENT OFFICE.

EMILY H. BUTTERFIELD, OF FARMINGTON, MICHIGAN, ASSIGNOR TO THETA KAPPA NU FRATERNITY, OF SPRINGFIELD, MISSOURI, A CORPORATION OF MISSOURI.

DESIGN FOR A BADGE.

Application filed June 24, 1925. Serial No. 13,870. Term of patent 14 years.

To all whom it may concern:

Be it known that I, EMILY H. BUTTERFIELD, a citizen of the United States, residing at Farmington, in the county of Oakland and State of Michigan, have invented a new, original, and ornamental Design for a Badge, of which the following is a specification, reference being had to the accompanying drawing, forming part hereof, wherein the figure shows an elevation of my new badge.

I claim:

The ornamental design for a badge, as shown.

EMILY H. BUTTERFIELD.
